(57) **CLAIM**

The ornamental design for an automated petri plate assessment system, as shown and described.

DESCRIPTION

FIG. 1 is a front perspective view of an automated petri plate assessment system showing our new design;

FIG. 2 is a rear view thereof;

FIG. 3 is a front view thereof;

FIG. 4 is a right view thereof;

FIG. 5 is a left view thereof;

FIG. 6 is a bottom view thereof; and,

FIG. 7 is a top view thereof.

The broken lines in the drawings depict parts of the automated petri plate assessment system that form no part of the claim.
